UNITED STATES PATENT OFFICE.

BRUCE MEEK AND FRED W. MILLER, OF DES MOINES, IOWA.

DESIGN FOR A SIGN.

• 58,155.

Specification for Design. Patented June 14, 1921.

Application filed July 8, 1919. Serial No. 309,519. Term of patent 3½ years.

To all whom it may concern:

Be it known that we, BRUCE MEEK and FRED W. MILLER, citizens of the United States, and residents of Des Moines, in the county of Polk and State of Iowa, have invented a certain new, original, and ornamental Design for a Sign, of which the following is a specification, reference being had to the accompanying drawing, forming part thereof.

The figure shows a front view of a sign embodying our invention.

We claim:

The ornamental design for a sign, as shown.

Des Moines, Iowa, April 26, 1919.

BRUCE MEEK.
FRED W. MILLER.
